DESIGN FOR A KNIFE

Thomas Holman Bryant, Sr., Louisville, Ky., assignor to Frankfort Distilleries, Incorporated, Louisville, Ky., a corporation of West Virginia

Application April 25, 1940, Serial No. 91,949

Term of patent 14 years

To all whom it may concern:

Be it known, that Thomas Holman Bryant, Sr., a citizen of the United States, residing at Louisville, in the county of Jefferson and State of Kentucky, has invented a new, original, and ornamental Design for a Knife, of which the following is a specification, reference being had to the accompanying drawing, forming part thereof, wherein—

I claim:

The ornamental design for a knife, as shown.
